UNITED STATES PATENT OFFICE

106,005

DESIGN FOR A DRESS

Samuel Chapman, New York, N. Y.

Application July 28, 1937, Serial No. 70,688

Term of patent 3½ years

To all whom it may concern:

Be it known that I, Samuel Chapman, a citizen of the United States of America, residing in the city of New York, county of New York, and State of New York, have invented a new, original, and ornamental Design for a Dress, of which the following is a specification, reference being had to the accompanying drawing, forming part thereof.

I claim:

The ornamental design for a dress, substantially as shown.

SAMUEL CHAPMAN.
